Primary Examiner—Terry A. Wallace

(57) **CLAIM**

The ornamental design for a container cover, as shown and described.

DESCRIPTION

The above and other aspects of the present invention will be more apparent from the following more particular description thereof, presented in conjunction with the following drawings wherein:

FIG. 1 is a front perspective view of the invention;

FIG. 2 is a back view of the invention;

FIG. 3 is a front view of the invention;

FIG. 4 is a top view of the invention; and,

FIG. 5 is a bottom view of the invention.

The broken lines are for illustrative purposes only and form no part of the claimed design.
